(57) **CLAIM**

The ornamental design for a baluster, as described and shown.

DESCRIPTION

FIG. 1 is a top front perspective view of the baluster of the present design;

FIG. 2 is a bottom front perspective view of the baluster of FIG. 1;

FIG. 3 is a front elevation view of the baluster of FIG. 1 (side and back views are identical); and,

FIG. 4 is a top view of the baluster of FIG. 1 (bottom view is identical).

The claimed design is broken in the center to indicate indeterminate length.
